UNITED STATES PATENT OFFICE

ABRAHAM SLOTOFF, OF BROOKLYN, NEW YORK

BATHING GARMENT

Application filed December 10, 1931. Serial No. 580,099.

Important objects of the present invention are, to provide a bathing garment comprising a waist having a low cut back and provided with improved means to hold the bust-covering portion of the garment snugly and securely fitted to the wearer, and to provide such a garment having several alternative means to hold the bust-covering portion snugly and securely fitted and to render the garment convertible to vary its appearance at the back.

Other objects of the invention will appear hereinafter.

In the drawing, Fig. 1 is a rear view of the improved garment;

Fig. 2 a reduced rear view of the garment upon a wearer and showing one adjustment of the garment;

Fig. 3 a view similar to Fig. 2 showing another adjustment of the garment; and

Fig. 4 a view similar to Figs. 2 and 3 showing another adjustment of the garment.

In the present instance the garment is of a union type and comprises a body or waist 1, and trunks 2 disposed within the lower, skirt portion of the waist and stitched thereto around the waist line. These parts may be separable, however. At its front and sides the waist is formed to cover the bust of the wearer to a required degree and at the back

it is low cut to define an approximate V extending from points directly beneath the arms of the wearer downward to a central point just above the waist line. Below the V cut the waist has a belt 3 which may be either

secured or detachable. Secured to or formed with the bust-covering portion are shoulder straps 4 which converge at the back of the garment and extend downward to a point below the central lowermost point of the V cut.

At their lower ends said straps are superposed and stitched to the inner side of the garment back, as at 5. One of the straps has a button 6 stitched upon its outer face and the other strap has a buttonhole 7 to receive

the button. Each strap has a button 8 stitched to its inner face at a point spaced below the aforesaid button or buttonhole. At its opposite sides the waist has two transverse tension straps or strands 9. The latter are se-

curely stitched at one end to the inner mar-

gins of the V cut at points spaced slightly below and back of the arms of the wearer. At their free ends the straps 9 have buttonholes 10 engageable with the buttons 8 of the shoulder straps. The waist and trunks of the garment and the straps 8 and 9 are all preferably made of knitted fabric. They may be made of other materials, however.

In one adjustment of the garment, shown in Fig. 2, the shoulder straps are unbuttoned and they converge clear to their lower anchorage at the bottom of the V cut. At opposite sides of the V cut the straps 9 are folded beneath the bust-covering portion of the waist and are concealed thereby.

In the adjustment of the garment shown in Fig. 3, the buttonhole 7 of one shoulder strap is engaged with the button 6 of the other strap. Thereby the straps are held sharply converged to a point located between the shoulder blades of the wearer and the straps exert a tension upon the bust-covering portion which holds it snugly fitted to the wearer. Below their buttoned point the shoulder straps are superposed and extend straight downward to their lower anchorage. In this adjustment of the garment also, the side straps 9 are folded out of sight beneath the bust-covering portion of the garment.

Fig. 4 shows an adjustment of the garment wherein the side tension straps 9 are employed. In this adjustment the shoulder straps are unbuttoned from each other and the straps 9 are extended rearward and the button hole of each is engaged to the button 8 of the adjacent shoulder strap. The straps then exert a rearward tension upon the bust-covering portion and hold the latter snugly and securely fitted.

It will be seen that my invention provides for more neat and secure fitting of the garment and also renders the garment convertible to change its style and to obtain an even sun tan at the back. In the adjustment shown in Fig. 3 the upper portions of the shoulder straps are disposed near the neck of the wearer and the lower portions of the straps are disposed at the center of the back. In the adjustments shown in Figs. 2 and 4 the straps are spread apart to uncover areas of

the back which were covered by the straps in their first adjustment. Also, in Figs. 2 and 3 the side tension strips are folded under to uncover areas of the back which they covered in the adjustment of Fig. 4. Thus the entire area of the back within the V cut of the waist may be evenly tanned without removing the straps from the shoulders and without releasing the bust-covering portion 10 of the garment.

What I claim is:

1. As an article of manufacture, a bathing garment comprising a waist having a bust-covering portion and a low-cut open back, a pair of shoulder straps connected at the front to the bust-covering portion and converging downward at the back within the back opening and having their lower end portions superposed and anchored to the lower 15 edge of the back opening, releasable fastening means carried by said straps to fasten them together at a medial point thereof at the back and hold them superposed between said point and their anchorage at the back, a 20 pair of transverse tension strips at opposite sides of the back opening and each anchored at one end to an inner edge margin of the back opening approximately at the bust level and being foldable to concealed positions 25 beneath the bust-covering portion, and releasable fastening means carried by the shoulder straps and said tension strips to secure the opposite end of each tension strip to the adjacent shoulder strap.
2. As an article of manufacture, a bathing garment comprising a waist having a bust-covering portion and a low-cut open back, a pair of shoulder straps connected at the front to the bust-covering portion and converging 40 downward, at the back within the back opening and having their lower ends superposed and anchored to the lower edge of the back opening, and releasable fastening means carried by said straps to fasten them together 45 at a medial point thereof at the back and hold them superposed and flat between said point and their anchorage at the back.
3. As an article of manufacture, a garment comprising a waist having a bust-covering portion and an approximately V-cut low back, a pair of shoulder straps connected at the front to the bust-covering portion and converging downward at the back and having their lower ends superposed and anchored 50 to the waist at the bottom of the V cut to form a V pattern within said cut in one adjustment of the strap, releasable fastening means carried by said straps to fasten them together in another adjustment at a medial 55 point thereof at the back and hold them superposed and flat between said point and their anchorage at the back to form a Y pattern within said V cut, said fastening point being located materially nearer the shoulders than to the bottom of the V cut, a pair of 60

transverse tension strips at opposite sides of the back opening and each anchored at one end to the waist at an edge margin of the back opening approximately at the bust level, and means to releasably fasten each of said tension strips to the adjacent shoulder strap below said first fastening means when the straps are in said V adjustment and combine with the straps to form still another pattern 70 in the V cut at the back, said tension strips being foldable to concealed positions beneath the bust-covering portions of the garment 75 when released from the straps.

4. As an article of manufacture, a garment comprising a waist having a bust-covering portion and an approximately V-cut low back, a pair of shoulder straps connected at the front to the bust-covering portion and converging downward at the back and having their lower ends superposed and anchored to the waist at the bottom of the V cut to form 80 a V pattern within said cut in one adjustment of the strap, and releasable fastening means carried by said straps to fasten them together in another adjustment at a medial point 85 thereof at the back and hold them superposed and flat between said point and their anchorage at the back to form a Y pattern within said V cut, said fastening point being located materially nearer the shoulders than to the bottom of the V cut.

5. As an article of manufacture, a bathing garment comprising a waist having a bust-covering portion and a low-cut open back, a pair of shoulder straps connected at the front to the bust-covering portion and converging downward, at the back within the back opening and having their lower ends superposed and anchored to the lower edge 100 of the back opening, and fastening means carried by said straps releasably holding them in flat superposed relation between their point of anchorage at the back and a point medial of their lengths.

In testimony whereof I hereunto affix my 110 signature.

ABRAHAM SLOTOROFF.
